UNITED STATES PATENT OFFICE.

ARTHUR J. SMITH, OF HAZLETON, PENNSYLVANIA.

PAPER-BAG SEAL.

1,128,192.

Specification of Letters Patent.

Patented Feb. 9, 1915.

Application filed October 13, 1914. Serial No. 866,529.

To all whom it may concern:

Be it known that I, ARTHUR J. SMITH, a citizen of the United States, residing at Hazleton, in the county of Luzerne and State of Pennsylvania, have invented a new and useful Paper-Bag Seal, of which the following is a specification.

The present invention appertains to a paper bag seal or fastener, and aims to provide a strip or ribbon applied to the bag or sack in a novel manner and provided with glue, mucilage or adhesive material thereon, whereby when the bag or sack is filled and the mouth portion thereof folded so as to close the bag or sack, the strip or ribbon may be passed over the top of the bag and secured to the bag for holding the same closed in a thoroughly practical manner, and without the employment of the usual binding 20 cord or string.

The present invention also aims to provide a securing or binding means of the nature indicated, eliminating with the use of string, and which will permit the bag or sack to be 25 readily and inexpensively sealed in closed condition, whereby the package will be neat in appearance, and will not be liable to open accidentally.

A further object of the present invention, 30 is to assemble the strip or ribbon with the bag or sack in a unique manner, whereby the bag or sack may be handled in the usual manner, the strip or ribbon being exposed, and without the liability of the strip or ribbon to project loosely from the bag or sack, as would be liable to cause the strip or ribbon to be torn loose.

A still further object of the invention is 35 to so position the securing strip or ribbon upon the bag or sack, that it will not become accidentally displaced, and in order that the same will not interfere with the closing of the bag or sack, but may be readily loosened and then applied over the top of the package after the bag or sack has been closed.

It is also within the scope of the invention, 40 to provide a seal or securing device of the nature indicated, which may be readily and inexpensively applied to the bag or sack, which will not appreciably encumber the bag or sack in the shipping or handling thereof, and which will be convenient, practical and efficient in its use.

With the foregoing and other objects in 45 view, which will appear as the description proceeds, the invention resides in the com-

bination and arrangement of parts and in the details of construction hereinafter described and claimed, it being understood that changes in the precise embodiment of the invention herein disclosed can be made within the scope of what is claimed, without departing from the spirit of the invention.

The invention has been illustrated in its preferred embodiment in the accompanying 50 drawing, wherein:—Figure 1 is a perspective view of a folded bag or sack having the securing strip or ribbon applied thereto. Fig. 2 is a perspective view of the bag or sack folded or opened up, and illustrating 55 the securing strip or ribbon in loosened position. Fig. 3 illustrates in perspective, the bag or sack as being filled, closed and sealed.

The present seal or fastener is assembled with a folded paper bag or sack, embodying the front 1, back 2, folding or bellows sides 3, and the satchel bottom 4. The satchel bottom 4 is folded against the back 2, the back 2 being folded upon the transverse fold lines 5 adjacent the lower end 60 thereof. The bag or sack is illustrated in folded position in Fig. 1.

The present seal or fastener embodies a strip or ribbon 6 of paper or other suitable material, having one end secured, as at 7, by 65 means of glue or other adhesive material to the back 2 of the bag or sack, intermediate the ends and side edges of the said back. The free portion of the strip or ribbon 6 is bent back, the strip being doubled upon the 70 transverse fold line 8 intermediate its ends, to provide the inner portion 9 adjacent the back 2, and the outer portion 10 overlying the portion 9. The bend or fold 8 of the strip 6 terminates short of the mouth or 75 upper end of the bag or sack, as clearly seen in Fig. 1, and the free end 11 of the strip is tucked between the folded satchel bottom 4 and the back 2. Thus, the free end 11 of the strip 6 being projected or extended under the folded satchel bottom 4, will hold the outer portion 10 of the strip snugly in 80 place against the body of the bag or sack, and consequently, the entire strip 6 will be held snugly in place, and will not be liable 85 to work loose when handled in the ordinary manner. The strip, as applied to the bag or sack, will not encumber the same, and it will be noted that the strip may be readily and inexpensively applied to the sack or bag 90 either manually or mechanically.

One side of the strip 6 is provided with

glue, mucilage, or other adhesive material, as at 12, the said adhesive material being disposed upon the inner side of the portion 9 of the strip and upon the outer side of 5 the outer portion 10. The adhesive material 12 extends throughout the length of the strip.

In use, when the bag or sack is unfolded or opened, as seen in Fig. 2, the free end 11 10 of the strip or ribbon 6 will be released by the bottom 4, and the portions 9 and 10 of the strip will then swing downwardly and outwardly, as seen in Fig. 2, to enable the mouth portion of the bag or sack to be 15 folded so as to close the bag after the same has been filled. Then, after the upper end of the bag has been folded and closed, as indicated at 13 in Fig. 3, the strip or ribbon 6 may be readily swung over the upper 20 end of the package, after the adhesive material 12 has been moistened, and which will enable the strip 6 to be readily secured over the upper end of the package and against the front 1. It will be observed that the end 25 7 of the strip 6 being attached previously to the back 2, and the strip assuming the position illustrated in Fig. 2, when the bag is unfolded, will enable the strip to be readily moistened and handled for applying it to 30 the package or bundle, as seen in Fig. 3.

The strip or ribbon 6 is not excessively long, and extends from the back, over the upper end of the package, and thence practically down the front 1. In this manner, 35 the minimum amount of material is only necessary, without detracting from the security of the seal or fastener.

The present seal or fastener therefore

eliminates the use of the ordinary tying string, which requires considerable time and 40 trouble in applying the same. With the present device, the fastening means is carried in a convenient and handy position by the bag or sack, and may be quickly and conveniently applied to the package. Furthermore, with the present device, when the package is sealed, or bound by the strip or ribbon, the package will present a neat and attractive appearance, and will not be liable 45 to break open accidentally. 50

Having thus described the invention, what is claimed as new is:—

1. The combination with a folded paper bag having a folded satchel bottom, of a strip having one end attached to the bag and 55 having adhesive material thereon, the strip being doubled upon itself and having its free end tucked under the folded bottom of the bag.

2. The combination with a folded paper 60 bag having a satchel bottom folded against the back thereof, of a strip having one end attached to the back of the bag, the strip being provided with adhesive material, and being doubled upon itself, the free end of 65 the strip being tucked between the said folded bottom and back of the bag, and the bend of the strip terminating short of the mouth of the bag.

In testimony that I claim the foregoing 70 as my own, I have hereto affixed my signature in the presence of two witnesses.

ARTHUR J. SMITH.
